CLAIM

The ornamental design for a conveyor pulley, as shown and described.

DESCRIPTION

FIG. 1 is a top perspective view of the conveyor pulley; FIG. 2 is a bottom perspective view of the conveyor pulley; FIG. 3 is a side perspective view of the conveyor pulley; FIG. 4 is an opposite side perspective view of the conveyor pulley; FIG. 5 is a front perspective view of the conveyor pulley; FIG. 6 is an end view of the conveyor pulley, the opposite end view being a mirror image; FIG. 7 is a front elevation view of the conveyor pulley; FIG. 8 is a rear elevation view of the conveyor pulley; FIG. 9 is a top plan view of the conveyor pulley; and, FIG. 10 is a bottom plan view of the conveyor pulley. The broken lines shown in the figures are for the purpose of illustrating portions of the conveyor pulley and form no part of the claimed design.

1 Claim, 5 Drawing Sheets
